FURNACE

Augusto Graf, Mexico, D. F., Mexico

Application November 14, 1930, Serial No. 495,711

9 Claims. (Cl. 110—75)

The invention relates to that type of furnace which is adapted for the use of fuel either of liquid or pulverized form, in which the fuel is injected or blasted into the fire-box of the furnace, air being introduced in such manner as to commingle with it and supply the oxygen necessary to combustion.

Complete combustion is secured only by a thorough admixture of the air with the fuel. Theoretically such admixture is possible only by prolonging the period of combustion or by the development of turbulence. Practically inasmuch as the air currents are introduced at high velocity and the size of the furnace chamber is restricted, particularly in locomotives in connection with which the invention is disclosed, the duration of the burning period cannot be sufficiently prolonged and turbulence must be depended upon.

Furthermore, the difficulty of securing an admixture of air with all portions of the fuel stream is increased by the fact that such stream usually assumes a fan shape.

In practice the supply of air is wholly or mainly provided through openings other than that at which the fuel is admitted, and the object of the present invention is to provide for the admission of air through a plurality of ports so configured and arranged that the entering air jets assail the column of fuel from different directions, thereby insuring a complete admixture of air and fuel within the combustion zone.

A preferred embodiment of the invention, and one which has proved to be highly efficient, is hereinafter described and is illustrated in the accompanying drawing, in which

Fig. 1 is a detail central longitudinal vertical section of the fire-box and boiler of a locomotive;

Fig. 2 is a plan view on the line 2—2 of Fig. 40 1; and

Fig. 3 is a detail section of the fire-box on the line 3—3 of Fig. 2.

A portion of a locomotive boiler is represented at 10. The fire-box thereof, generally designated as 11, is bounded by a rear wall 12, which constitutes a part of the backhead of the boiler in which is provided a door opening 13; a flue sheet 14, and a bottom metallic wall 15, the latter having a vertical portion 16 through which a fuel nozzle 17 is entered, such nozzle being preferably directed backwardly and slightly upwardly toward the wall 12, in order that the flame may circulate completely through the fire-box before entering the flues 18 which lead from the flue sheet 14.

The side, end and top walls of the furnace are water protected, and the bottom wall is preferably lined with masonry, as shown at 19, which may extend upwardly some distance along the vertical walls and provide for the desired arrangement of air ports which enter through it.

The air induction ports are formed in the bottom of the fire-box, and are preferably arranged in line directly below the fuel stream. They are inclined from the vertical so as to deliver obliquely to the fuel stream but in the general direction of its flow. The adits of the ports are oblong in form, their major axes diagonally crossing the vertical plane of the fuel stream, such axes of adjacent ports being oppositely inclined.

By this arrangement and shaping of the ports the fuel stream is assailed obliquely from below and obliquely on each side of its vertical plane, and a thorough admixture of air with the fuel is secured by the resulting turbulence created. The air may be introduced in any desired manner, ordinarily induction due to furnace draft being sufficient to provide both the necessary volume and velocity.

As shown in the drawing the ports are six in number, those designated by the numerals 20, 22 and 24 being inclined forwardly from left to right relatively to the vertical plane, and alternate ports, designated 21, 23 and 25, being oppositely inclined. The particular shape and disposition of the ports, either relatively or with reference to the vertical plane of the fuel stream, is not, however, of the essence of the invention in its broader aspects. For example, the location of the ports of the two sets need not necessarily follow the same line, and the obliquity of the several ports, particularly as to the vertical plane, may be varied.

I claim as my invention—

1. A furnace having a fire-box, a fuel nozzle 40 delivering into the chamber of the box through a vertical wall, a series of oblong air induction ports in the bottom of the box, the several ports delivering to the fuel stream obliquely to the general direction of its flow, the major axes of 45 alternate ports being oppositely inclined to the vertical plane of the axis of the stream.

2. A furnace having a fire-box, a nozzle for pulverized fuel delivering into the fire-box through a vertical wall thereof, a series of transversely oblong slots in the bottom of the box for delivering air thereto, the major transverse axes of alternate slots crossing the vertical plane of the axis of the stream at opposite inclines, and the longitudinal axes of the slots being forwardly 55

- inclined with reference to the direction of travel of the stream.
3. In a pulverized fuel furnace, in combination, a fire-box, a nozzle delivering a stream of fuel into the chamber of the fire-box approximately normal to the wall thereof through which it enters, and a set of oblong air ports in a wall of the chamber lateral as to the stream, the major transverse axes of which are oblique to a plane common to the set of ports and to the stream, such axes of adjacent ports being oppositely inclined.
4. A furnace having a fire-box, a fuel nozzle for discharging an approximately horizontal stream into the chamber of the box, and means for delivering air currents obliquely and alternately to the opposite sides of the stream and in the general direction of its flow.
5. A furnace having a fire-box, a fuel nozzle for discharging an approximately horizontal stream into the chamber of the box, and means for delivering a succession of air currents obliquely to the opposite sides and bottom of the stream and in the general direction of its flow, alternate currents attacking the fuel stream from opposite sides.
6. In a pulverized fuel furnace, in combination, a fire-box, a nozzle delivering a fuel stream into the chamber, and a set of air ports in a wall of the chamber lateral as to the stream, such ports having the form of slots, the major transverse axis of the opening of each obliquely crossing a plane common to the path of the stream and to the slots, each slot discharging obliquely to the stream path and in the general direction of the advance of the fuel, the major transverse axes of adjacent slots being oppositely inclined with reference to the stream path.
7. In a furnace, a nozzle for discharging a fuel stream into the combustion chamber, air ports discharging obliquely into the stream and in the general direction of its flow, adjacent air streams being oppositely inclined and following non-intersecting paths.
8. In a furnace, a nozzle for discharging a fuel stream into the combustion chamber, two sets of air ports discharging obliquely across and in the general direction of flow of the fuel stream, adjacent air streams being oppositely inclined and following non-intersecting paths.
9. A furnace having a fire-box, a fuel nozzle delivering a stream of fuel into the chamber thereof, a plurality of air ports in a wall of the box approximately parallel with the fuel stream, such ports being arranged in a line disposed in the same general direction as the fuel stream, the several ports being oblong in cross-section, the longer transverse axes of adjacent ports occupying intersecting planes, the longitudinal axes of the ports being oblique to horizontal and vertical planes taken longitudinally through the fuel stream, such axes of adjacent ports being oppositely inclined.

AUGUSTO GRAF.
